UNITED STATES PATENT OFFICE.

THOMAS KING STANLEY, OF ST. LOUIS, MISSOURI.

DESIGN FOR A LACE COVER OR SPREAD.

SPECIFICATION forming part of Design No. 30,930, dated May 30, 1899.

Application filed April 17, 1899. Serial No. 713,415. Term of patent 14 years.

To all whom it may concern:

Be it known that I, THOMAS KING STANLEY, a citizen of the United States, residing at St. Louis, State of Missouri, have invented and produced a new and original Design for Lace Covers or Spreads, of which the following is a specification, reference being had to the accompanying drawing, forming a part thereof.

10 The drawing is a plan view of a lace cover or spread, showing my new design.

As shown in the drawing, the leading or material features of my design consist of a lace cover or spread having an ornamental border 1, a three-sided design 2, located adjacent or at a suitable distance from the border 1 and running parallel with the same, and a central figure of ornamental design 3,

located within the three-sided design 2, all of which is clearly shown in the drawing. 20

A lace cover or spread, designed as herein shown and described, will give the bed upon which it is placed a very neat and attractive appearance, especially where a lace-covered roll or bolster is used in connection therewith. 25

Having described my invention, what I claim as new, and desire to secure by Letters Patent, is—

The design for a lace cover or spread, substantially as herein shown and described. 30

In testimony whereof I affix my signature in presence of two witnesses.

THOMAS KING STANLEY.

Witnesses:

C. F. KELLER,

ALFRED A. MATHEY.
